UNITED STATES PATENT OFFICE.

BROR A. UTTER, OF CHICAGO, ILLINOIS.

DESIGN FOR A CASKET-BAR BRACKET OR LUG.

56,040.

Specification for Design.

Patented Aug. 10, 1920.

Application filed May 12, 1919. Serial No. 296,705. Term of patent 3½ years.

To all whom it may concern:

Be it known that I, BROR A. UTTER, a citizen of the United States, and residing in the city of Chicago, county of Cook, and State of Illinois, have invented a new, original, and ornamental Design for a Casket-Bar Bracket or Lug, of which the following is the specification, reference being had to the accompanying drawings, forming a part thereof.

In the drawings:

Figure 1 is a front elevation of a casket

bar bracket or lug illustrating the design embodying my invention.

Fig. 2 is a rear elevation thereof.

Fig. 3 is a side elevation thereof.

I claim:

The ornamental design for a casket bar bracket or lug, as shown.

BROR A. UTTER.
